UNITED STATES PATENT OFFICE

2,355,984
COAT HANGER
Elmer H. Lupton, Ilchester, Md.
Application August 28, 1942, Serial No. 456,553
1 Claim. (Cl. 223—87)

This invention refers to clothing equipment and more particularly to coat hangers for supporting wearing apparel. It has among its objects to provide a coat hanger that will hold trousers, coats, dresses and other garments in such a manner as to keep their form and avoid the undue creasing of parts. Another object is to have the device designed to reinforce itself and produce a strong structure, even when made of paper, cardboard and other relatively weak materials. A further object is to have the form such that the article may be stamped out of a flat piece of material and then easily bent or formed to give it the strength and effectiveness desired for the purposes for which it is used. A still further object is to arrange the coathanger so it will stay readily in place on a hanger bar or hook and have eliminated therefrom all sharp edges and points that might tend to injure the user or the garment on it or in the vicinity.

Lightness, surface to mark or print on and compactness are also features of this invention.

Other objects will become apparent as the invention is more fully set forth.

While coathangers have been punched out of flat material heretofore such have required separable metal hooks for the supporting element, and they have had edges that produced undesirable creases in pants and other garments hung upon them. In this invention, the blank is cut with an integral hook and all other parts integral with it, and the form is such that it is readily shaped to make the completed article ready for use without detriment to the apparel. It has no parts that can tear the clothing and it is light and strong. It has a certain amount of flexibility laterally that is very desirable in packing the clothing with the coathanger in a suit case or trunk, as it has not the rigidity which conventional wire and wooden ones have. Rigidity under these circumstances makes it hard to pack such items and when packed the rigid forms impress their shapes into the apparel. This is avoided by this invention. The coathanger has a special feature in its locking arrangement that is flexible and keeps the coathanger from loosening during the general movement and weighting caused by the hanging of coats etc. thereon.

In the drawing which illustrates a form of this invention:

Figure 1 is a front view of a coathanger embodying this invention;

Figure 2 is a full view of the unfolded blank as it is punched from a sheet of flat material;

Figure 3 is a sectional elevation taken along line 3—3 of Figure 1;

Figure 4 is a sectional elevation taken along line 4—4 of Figure 2, and

Figure 5 is a rear view of the form shown in Figure 1.

Similar reference characters refer to similar parts throughout the drawing.

In the drawing, 1 represents a coathanger blank having a substantial hook 2 formed on its upper portion for hanging the same on a horizontal pole or coathook, in a conventional manner. This hook includes a hump 22 for making it stay on a holding bar. A relatively large lower portion 3 is cut out at its lower border 4 adjacent the middle in the form of a polygon slot 5 with the two projecting fins 6 disposed to restrict the entrance portion of the slot and retain the locking member as indicated on the drawing. The middle portion 7 of the blank is formed with external outlines 8 suitable for contact with the garments placed upon it to be supported on the hanger. Its corners 9 are rounded to avoid pointed portions from sticking into them. A pyramidal piece 10 is cut in the middle portion of the form shown in Figures 2, 3 and 4 with its lower portion 11 connected to the blank to form a flexible hinged element on which the piece 10 may be swung. The piece 10 has a rectangular locking member 12 adapted to fit into the center part of the slot 5 and catch in back of the fins 6, when it is bent over into the position indicated in Figure 3. The opening 13 left by slitting out of the piece 10 serves as a means for handling the coathanger and as a space through which the garment may be attached to the lower portion if desired. The upper edges 14 are arranged to bind on these garments and prevents them from slipping off easily.

As the piece 10 is bent over, it is formed with a large flat surface 15 which serves as a ledge on which the garment etc. may rest without being creased thereby.

This ledge or flat surface 15 when braced by piece 10 serves to give it a truss effect and add stiffness to the coat hanger when in hanging position and prevent its bending in a longitudinal or lateral direction which the unsupported portion of the material cut flat would not provide. In packing, this ledge functions differently to its action while in hanging position, where the stiffness is fully used. When packed in a suitcase or trunk the weight of the clothes is eliminated from the ledge and does not tend to pull it to a horizontal position. The resiliency of the piece

10 tends to lift and remove the ledge with its stiffness, and allow the flatness resumed to become flexibly acting, so it may be packed adjustably and easily.

As the weight of the pants or other garment etc. inserted through the opening and resting on the ledge 15 increases, it tends to force the piece 10 downward. This makes the locking member 12 travel further down into the slot 5, until the points 16 contact the sides 17 of the slot 5, but in doing so stays in back of the projections 6 and keeps in place without unlocking when the load is removed from the ledge 15. The manner of inserting the member 12 is indicated in the drawing and does not seem to need further description.

The coats and the like are hung over the shoulder edges 8 and corners 9. The pants and narrower articles of clothing rest on the ledge and bar formed on the lower portion 3, with the piece 10 bent as described. Where the inner opening and ledge are not required, the piece 10 may be left in the opening 13 as it appears when the blank is first punched out, or it may be partially pushed out so as to open up the garment slightly for the admission of air during drying or airing. The form of the hook promotes its effectiveness and freedom for possible injury to the garments. While but one general form of the invention is shown in the drawing, it is not desired to limit this application to this particular form or in any other way otherwise than limited by the scope thereof, as it is appreciated that other forms could be made that would use the same principles and come within the scope of the appended claim.

Having thus described the invention, what is claimed is:

A coat and pants hanger of the class described consisting of a single blank of relatively thin flat material, having a central rectangular slot 5, a hook portion 10 having a straight bottom edge 11, a ledge portion 12 having a straight bottom edge 13, a bar portion 3 having a straight bottom edge 14, and a hinged flap 15, the hook portion 10 being arranged to be horizontally disposed and long enough for the use of a coat, the side edges of the blank being cut along converging lines to make an opening across the blank and to provide a hinged flap of the material of the blank arranged for bending over with its apiced portion rectangular in form and insertable in said slot for locking and resting therein, the hinged portion being bent horizontally out from the blank arranged to form a ledge for resting pants inserted through the said opening, the opening being formed to provide a restricted rectangular slot in its apiced portion and restricted relatively small horizontal slots at the bottom corners thereof for holding the sides of the pants placed therein tightly, the hook portion being formed in the same plane and positioned above the middle of the blank and formed with its hook cut to a form and rounded over to point downwardly and provide an internal spacing in the hook adapted for hanging on a nail or the like, said last mentioned spacing having an entrance directly under the pointing down portion of the hook and restricted by a relatively small hump rising closely to the hook so as to form therewith a restricted passage to the said spacing.

ELMER H. LUPTON.

comprising in combination, a single blank of relatively thin flat material cut peripherally into a contour having a straight bottom edge with a relatively small polygonal slot opening out and disposed at the middle thereof with sides directed inwardly to restrict the opening, the said edge being arranged to be horizontally disposed and long enough for the use of a coat, the side edges of the blank being perpendicular to the bottom edge and relatively short with inwardly directed upper edges in the same plane towards a hook formed in an apiced position thereon, of the same blank, the middle central portion of the whole blank being cut along converging lines to make an opening across the blank and to provide a hinged flap of the material of the blank arranged for bending over with its apiced portion rectangular in form and insertable in said slot for locking and resting therein, the hinged portion being bent horizontally out from the blank arranged to form a ledge for resting pants inserted through the said opening, the opening being formed to provide a restricted rectangular slot in its apiced portion and restricted relatively small horizontal slots at the bottom corners thereof for holding the sides of the pants placed therein tightly, the hook portion being formed in the same plane and positioned above the middle of the blank and formed with its hook cut to a form and rounded over to point downwardly and provide an internal spacing in the hook adapted for hanging on a nail or the like, said last mentioned spacing having an entrance directly under the pointing down portion of the hook and restricted by a relatively small hump rising closely to the hook so as to form therewith a restricted passage to the said spacing.
